Primary Examiner — Richard E Chilcot(74) *Attorney, Agent, or Firm* — Birch, Stewart, Kolasch & Birch, LLP(57) **CLAIM**

The ornamental design for an oven with gas range, as shown and described.

DESCRIPTION1. **Oven with gas range**

1.1 is a perspective view of an oven with gas range, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof; and

1.7 is a bottom plan view thereof.

1 Claim, 7 Drawing Sheets(56)
